(57) **CLAIM**

The ornamental design for an image for a portion of a display screen, as shown and described.

DESCRIPTION

FIG. 1 is a front view of an image for a portion of a display screen showing our new design; and,

FIG. 2 is an enlarged view of the claimed region.

The broken line showing of the display screen is for illustrative purposes only and forms no part of the claimed design.

1 Claim, 2 Drawing Sheets

FIG. 1

FIG. 2
